ELECTRICAL CONNECTION MEANS

Charles S. Penfold, Bronson, Mich., assignor to
H. A. Douglas Mfg. Co., Bronson, Mich., a corporation of Michigan

Continuation of application Serial No. 188,431,
February 3, 1938. This application December
5, 1939, Serial No. 307,701

5 Claims. (CL 200—163)

This invention relates generally to electrical switches and more particularly to electrical connection means whereby a plug conductor terminal of the snap type secured to a conductor may be detachably connected to the switch in a predetermined position for engagement with the bridge means of the switching mechanism.

This application is a continuation of my application Serial Number 188,431, filed February 3, 1938.

More specifically the invention is directed to a switchback provided with an aperture through which a plug conductor terminal of the snap type extends, and means for holding the terminal in the aperture in a position whereby the terminal may directly engage the bridge means of the switching mechanism. Such an arrangement is highly desirable electrically, since there is a direct connection between the conductor and the bridge means, and avoids the use of separate contact means permanently or detachably secured to a switchback, such as are now in commercial use.

Other objects and advantages of the invention will be apparent after reading the description hereinafter set forth in connection with the drawing annexed hereto.

Referring to the drawing:

Figure 1 is a top view of a switch;

Figure 2 is a longitudinal sectional view taken substantially on line 2—2 of Figure 1, and clearly shows the majority of details of construction;

Figure 3 is a section taken substantially on line 3—3 of Figure 2 with the plug conductor terminals omitted, and shows more in detail the construction of the detent means which are employed to retain the plug conductor terminals in a predetermined position with respect to the switchback, and

Figure 4 is a section of a part of a modified construction showing detent means assembled with a switchback in a different manner.

Referring to the drawing, 1 represents a metallic switch case. A bridge member 2, in the form of a plate and mounted on a carrier 3 of insulating material, is arranged for reciprocation within the casing through the agency of the switch handle 4. As clearly shown, the bridge member and its carrier is resiliently supported in the casing by means of a spring member 5 which is preferably secured to the carrier 3. The spring member 5 is preferably provided with resilient tongue portions 6, the convex portions of which slidably engage the bottom wall of the casing when the bridge member is reciprocated. It is to be understood that the switching mechanism shown, which includes the bridge member 2, its carrier 3, spring member 5, and handle 4, is merely illustrative and may assume other shapes and arrangements. More-

over, it is to be understood that it is immaterial if the bridge member is reciprocable, rotatable, or otherwise movable within the switch casing. It is also immaterial as to whether or not a spring such as 5 is placed under the carrier, as shown, or a suitable spring is arranged between the carrier and the bridge member.

10 A switchback generally designated 7 is secured to the open extremity of the switch casing and provides a cover therefor. The switchback may be secured to the casing in any suitable manner, but as here shown, the casing is preferably provided with a plurality of integral fingers 9 which are adapted to project within notches provided in the switchback and are clinched over and against the outer face of the switchback.

The switchback is preferably constructed of a plurality of superimposed sheets or members of insulating material. The outer members 10 and 11 are preferably of a greater thickness than the innermost member 12, but if so desired, all three members may be of the same thickness. Preferably, the complete thickness of the switchback, whether made up of a single member or a plurality of members of insulating material should be of a sufficient thickness whereby to prevent tilting of the plug conductor terminals which project through the switchback. The outer member 10 is provided with a pair of spaced apart circular apertures 13, and the outer member 11 with a pair of spaced apart circular apertures 14 which are of the same diameter as apertures 13, and cooperate with the apertures 13 whereby to provide tubular passages or guides for the plug conductor terminals.

15 The inner member 12 of the switchback is provided with a pair of spaced apart apertures 15 that are communicatively connected with the apertures 13 and 14. Any suitable means may be provided whereby to hold the plug conductor terminals in relation to the switchback so that the terminals may directly engage the bridge member 2, but as here shown, detent means 16 is arranged in each of the apertures 15. Each of the detent means 16 is preferably made of spring wire formed to provide a pair of complementary coacting circular portions 17 connected together by an offset bight portion 18. The bight portion 18 functions to improve the resilient action of the detent means and promotes its durability; or in other words, serves to eliminate the possibility of the detent means from taking a set, which would obviously destroy its effect of holding the plug conductor terminal in place. As clearly shown, each of the apertures 16 adjacent the portions 17 is of such a character that clearance is provided for the expansion of the portions 17 a predetermined extent whenever a plug conductor terminal is inserted into place.

The parallel portions 19 forming the bight 18 of each of the detent means will be effected to insure a proper grip upon the terminals whenever the portions 17 are expanded to the extent anticipated.

The plug conductor terminals 20, are preferably permanently joined to electrical conductors 21 by swaging, as indicated at 22. Each of the plug conductor terminals is preferably provided with a V-shaped groove 23 which is adapted to receive the coacting portions 17 of the detent means 16, and the arrangement is such that the terminals are held in a predetermined position in order that the conical contact 24 of each terminal projects beyond the outer member 11 of the switchback to be engaged by the bridge member 2.

It is to be understood that the tongue portions 6 of the spring 5 are of such a character that the bridge member and its carrier will be urged in a direction toward the plug conductor terminals 20, and that the spring 5 is not of sufficient resiliency to unseat the plug conductor terminals; or in other words, overcome the holding action created by the detent means 16.

Referring to the modified construction in Figure 4, the switchback is shown as being comprised of two members 50 and 51 of insulating material. Each member is provided with a recess 52 and an aperture 53. Recesses 52 are complementary to each other and register to provide a pocket for the detent means 54, and of course, the apertures 53 register to provide a terminal receiving aperture. This construction may be desirable in some instances.

In view of the foregoing, it will be evident that improved means are provided whereby a direct connection may be made between plug conductor terminals and a bridge member of a switch mechanism. It will also be evident that the plug conductor terminals in themselves provide contacts, and that the use of contacts either permanently or detachably connected to a switchback, which are now in commercial use, are avoided. Furthermore, such an arrangement is far more economical to manufacture than the present types of electrical connections now in use, and particularly those of the type where a plug conductor terminal is snapped into electrical connection means forming a contact on the switchback.

Having thus described my invention, it is obvious that various immaterial modifications may be made in the same without departing from the spirit of the invention; and, therefore, I do not wish to be understood as limiting myself to the exact form, construction, arrangement, and combination of parts herein shown and described.

I claim:

1. A switchback comprised of a plurality of superimposed members, an aperture provided in an intermediate member, and an aperture provided in each of the outer members cooperating with the aperture in said intermediate member, detent means arranged entirely within the aperture provided in said intermediate member, a plug conductor terminal of the snap type projecting through said apertures with the detent means functioning to retain said terminal in a predetermined position with its forward end extending beyond one of the outer members.

2. An electric switch including in combination, a casing, a movable bridge member arranged in

said casing, a piece of insulation carried by said casing, terminal receiving apertures provided in said insulation, terminals arranged in said apertures, abutment means provided on said terminals, separate snap connection means carried by said insulation encompassing and cooperating with said abutment means for holding a plug conductor terminal of the snap type in each aperture whereby the forward end of each terminal will directly engage said movable member when the latter is moved to a predetermined position.

3. An electric switch including in combination, a casing providing a chamber, a movable bridge member arranged in said chamber, a piece of insulation carried by said casing, terminal receiving apertures provided in said insulation, plug conductors of the snap type individually arranged in said apertures, separate resilient means carried by said insulation and located exteriorly of said chamber within the border of the insulation for independently encompassing and resiliently holding said plug conductor terminals whereby their forward ends are directly in engagement with said movable bridge member when the latter is moved to a predetermined position within said chamber, and means on said terminals cooperating with said separate resilient means for limiting the inward movement of said terminals when same are being independently plugged in said apertures.

4. An electrical switch including in combination, a casing, a movable bridge member arranged in said casing, a piece of insulation carried by said casing, terminal receiving apertures provided in said insulation, conductor wires having plug conductor terminals secured thereto, said terminals being adapted to be individually plugged into said apertures arranged in said terminals, separate connection means for each terminal carried by said insulation substantially encompassing each terminal and engaging each cooperating means for holding each terminal in a predetermined position in its aperture whereby the forward end of each terminal will be held to directly engage said movable bridge member when the latter is moved to a predetermined position.

5. An electrical switch including in combination, a casing providing a chamber, a movable bridge member arranged in said chamber, a piece of insulation carried by said casing, terminal receiving apertures provided in said insulation, plug conductors of the snap type individually arranged in said apertures, separate means carried by said insulation and located exteriorly of said chamber and substantially within the border of the insulation for independently receiving said plug conductor terminals, each of said terminals having a contact provided adjacent its inner end, each of said separate means being designed to hold the contact end of each terminal for engagement with said movable bridge member when the latter is moved to a predetermined position within said chamber, and means on each of said terminals set back from said contact and cooperating with said separate means for predeterminedly the specific location of each terminal axially within an aperture when the terminal is plugged therein.

CHARLES S. PENFOLD.
